UNITED STATES PATENT OFFICE.

GUSTAVE A. LOEBEN, OF PHILADELPHIA, PENNSYLVANIA, ASSIGNOR TO THE DE LUXE
BRUSH COMPANY, OF WILMINGTON, DELAWARE, A CORPORATION OF DELAWARE.

DEVICE FOR DISPENSING FLUID MATERIAL.

1,263,908.

Specification of Letters Patent. Patented Apr. 23, 1918.

Application filed December 2, 1916. Serial No. 134,695.

To all whom it may concern:

Be it known that I, GUSTAVE A. LOEBEN, a citizen of the United States, residing in Philadelphia, Pennsylvania, have invented 5 certain Improvements in Devices for Dispensing Fluid Material, of which the following is a specification.

My invention relates to that type of dispensing device in which pressure is imparted to the material by means of a forwardly moving plunger and the escape of the material is governed by means of a valve, and my improvements relate especially to the means for imparting forward 15 movement to the plunger and opening and closing the discharge-controlling valve.

In the accompanying drawings—

Figure 1 is a vertical sectional view of a dispensing device constructed in accordance 20 with my invention, the discharge controlling valve being closed;

Fig. 2 is a similar view with the discharge controlling valve open, and .

Fig. 3 is an enlarged horizontal section 25 on the line 3—3, Fig. 1, but omitting the brush head shown therein.

Referring in the first instance to Figs. 1 and 2 of the drawing, 1 represents a tubular casing for containing the fluid material, such 30 casing having at its forward end a contracted nozzle 2 through which the material is discharged. In the present instance I have shown the dispensing device as intended for use in connection with a brush to 35 which the material is to be supplied at intervals, the head 4 of said brush having screw connection with the casing and said screw connection being preferably of the multiple thread type so as to permit of quick 40 application or removal of the brush. The device is, however, available for other uses.

That portion of the forward end of the nozzle 2 which surrounds the discharge aperture constitutes a seat for a valve 5 45 which forms part of, is secured to, or is in connection with, a screw stem 6, so as to partake of the longitudinal movement of the latter. The screw stem 6 is disposed axially within the casing 1, and is in engagement with the threaded hub of a plunger 7, whose periphery fits snugly to the inner wall of the casing 1 and is prevented from turning within said casing either by frictional contact with said wall,

by an engaging tongue and groove, or other 55 equivalent means.

The rear end of the tube 1 is closed by a cap 8 and between said cap and a collar 9, secured to, forming part of, or otherwise in engagement with the screw stem 6, is interposed a coiled spring 10 which imparts downward thrust to the valve 5 and tends to keep it constantly in contact with its seat at the forward end of the nozzle 2, and thus prevent escape of material from the 65 latter. The spring 10 surrounds a stem 11 which extends from the collar 9 through an opening in the cap 8 and through a knob 12 to which it is secured so as to turn therewith, the periphery of said knob being 70 knurled or roughened so that it can be readily rotated by thumb and finger.

If it is intended to rotate the knob 12 by a clockwise movement the screw stem 6 is provided with a left hand thread as shown, 75 but if the movement of the knob 12 is intended to be counter-clockwise the thread should be right handed. In either case proper rotation of said knob 12 will cause forward movement of the plunger 7 within 80 the casing 1 and consequent exertion of pressure upon the mass of fluid material in said casing in advance of the plunger. The valve 5, however, will remain seated until the mass of material in advance of the plunger 85 opposes such resistance to further forward movement of the latter as to overcome the forward pressure of the spring 10, whereupon continued forward movement of the screw stem 6 will cause it to rise through 90 the hub of the plunger, thereby compressing the spring 10 and opening the valve 5, as shown in Fig. 2, so as to permit discharge of the fluid material from the nozzle 2.

As soon, however, as the resistance of the 95 mass of material in advance of the plunger is less than the forward pressure of the spring 10, the latter will expand and force the screw stem and plunger 7 forwardly in the casing so as to again close the valve 5 100 and cut off the escape of material from the nozzle 2.

Between the valve 5 and the forward end of the threaded stem 6 is interposed a valve stem which rotates with said screw stem 105 and extends throughout the length of the nozzle 2. The valve stem is, in respect to the screw stem, reduced in thickness on each

side so as to present a flat blade 13 having at each end an enlarged rib 14 which, by preference, is rounded on its outer face and bears snugly against the inner wall of the 5 nozzle 2, as shown in Fig. 3.

When, therefore, the screw stem 6 is rotated, the blade 13 will stir up and agitate the mass of material contained within the nozzle and will prevent the stiffening or 10 hardening of said mass to which, owing to its limited bulk, it would otherwise be subject. At the same time, the ribs 14, at the ends of the blade 13, scrape the inner wall of the nozzle and prevent the material from 15 adhering thereto.

If the material to be dispensed is contained in a cartridge or vessel to be disposed within the casing 1, the plunger 7 will bear against the inner wall of said 20 cartridge and means will be employed both to prevent rotation of the plunger in the cartridge and rotation of the latter in the casing.

I claim:

25 1. In a device for dispensing fluid material, the combination of a non-rotating holder for said material, a plunger for im-

parting pressure to the material, and a rotatable screw stem for engaging said plunger and effecting forward movement of the 30 same, said stem carrying a valve for governing the escape of the material from the holder and wings which contact with the surrounding wall of the non-rotating holder, and, as the screw stem is rotated, 35 serve to scrape the material from said wall.

2. The combination, in a device for dispensing fluid material, of a non-rotating holder for said material, a plunger for imparting pressure to the material, and a rotatable screw stem engaging said plunger and effecting forward movement of the 40 same, said holder having at its forward end a contracted discharge nozzle with valve seat therein, said screw stem carrying a 45 valve adapted to said seat, and wings which contact with the wall surrounding the contracted discharge nozzle at the forward end of the holder and, as the screw stem is rotated, serve to scrape the material from said 50 wall.

In testimony whereof I have signed my name to this specification.

GUSTAVE A. LOEBEN.
